MANUFACTURE OF BUTYLENES

Filed Jan. 14, 1943

UNITED STATES PATENT OFFICE

2,388,099

MANUFACTURE OF BUTYLENES

Clare Kenneth Viland, Martinez, and Herschel Y. Hyde, Associated, Calif., assignors to Tide Water Associated Oil Company, San Francisco, Calif., a corporation of Delaware

Application January 14, 1943, Serial No. 472,412

9 Claims. (Cl. 260—683)

This invention relates to the manufacture of olefinic feed stock for alkylation and similar processes where a high concentration of butylenes is desirable and has for a principal object the manufacture of a C₄ fraction containing unusually high percentages of olefinic hydrocarbons.

Another object of the invention is to provide materials peculiarly adapted for pyrolytic conversion into butylenes.

A further object is to reduce the quantity of normal butane commonly present in stocks charged to alkylation or similar processes thereby increasing the plant capacity by elimination of a large proportion of those hydrocarbons not entering into the reaction.

Other objects will be apparent from the following description.

In the manufacture of modern aviation gasoline the alkylation process has become one of the most commonly used methods of obtaining gasoline fractions of high anti-knock rating. As is well known, this process comprises the formation of branch-chain paraffins chiefly in the boiling range of the octanes by the chemical combination of isobutane with butylenes.

The quantity of alkylate which may be produced in any given area, therefore, is limited by the available supply of isobutane and butylenes as well as by the capacity of the alkylation plants. Present demands for aviation gasoline have resulted in the consumption of practically the entire supply of naturally occurring isobutane and numerous refineries have undertaken the installation of isomerization processes to augment the supply thereof. The chief source, if not the entire supply, of butylenes is obtained as by-products from pyrolytic processes, such as cracking and polymerization, which are primarily designed for the manufacture of hydrocarbons within the gasoline boiling range. Due to modern demands for butylenes for alkylation purposes numerous pyrolytic plants are being operated principally for their butylene production.

As commonly practiced, the butylenes for the alkylation process are obtained by isolating a C₄ cut from the products of the pyrolytic cracking and/or polymerization processes. Ordinarily this C₄ cut will contain from about 25% to 45% of butylenes, the remainder being chiefly normal butane. As the normal butane cannot be readily fractionated from the butylenes without the use of extensive fractionating equipment, it is common practice to charge the entire C₄ cut to the alkylation process, along with the required amounts of isobutane. As the normal butane does not enter into the alkylation reaction, it passes through the plant unchanged and is fractionated from the products of the reaction. This procedure offers difficulties, however, when normal butane is present in large amounts. First

the throughput capacity of the alkylation reactor is reduced in proportion to the amount of the inert normal butane which is present. Second, in order to separate the normal butane from the products, a heavy load is placed on the fractionating equipment of the alkylation plant. Third, since the alkylation process requires the recirculation of large amounts of isobutane for the proper functioning of the process, the separation therefrom of the inert normal butane always results in the loss of substantial quantities of valuable isobutane into the normal butane due to imperfect fractionation. From the above it is seen that it is desirable to charge to the alkylation process a C₄ cut with as low a content of normal butane as possible.

The present invention provides a means whereby there can be obtained from a pyrolytic process a C₄ cut containing in the order of 60% to 80% of butylenes, the remaining 40% to 20% being composed of nearly equal quantities of isobutane and normal butane. By the use of such a C₄ cut the above difficulties are greatly alleviated and the capacity of a conventional alkylation plant is thereby greatly increased. As the isobutane enters the alkylation reaction, the quantity of unreactive material (normal butane) is thus reduced to a minimum.

Briefly described the invention comprises subjecting normal pentane to pyrolytic decomposition in the presence of substantial amounts of C₂ and C₃ hydrocarbons. When normal pentane is subjected to temperatures in the range of 1000° F. to 1300° F., it is decomposed into various olefinic and paraffinic hydrocarbons as a result of several more or less simultaneously occurring reactions of which the following appear to predominate:

In accordance with the invention substantial quantities of propane, propylene, ethane, and/or ethylene are mixed with the normal pentane prior to carrying out the decomposition. The presence of the C₂ and especially the C₃ hydrocarbons tends to suppress reactions (1) and (2) and thereby increases the amount of material undergoing reaction (3), resulting in the formation of a large amount of butylenes.

Under the temperature conditions of the reaction, and especially in the temperature range of 1050° F. to 150° F., there occur, simultaneously with the decomposition of the normal pentane, polymerizing reactions among the C₂ and C₃ hydrocarbons present resulting in the formation of additional quantities of butylene together with a large quantity of polymer gasoline of good anti-knock value. Isobutane, normal butane, and, in

minor proportions, polymer tars and other products are also formed. As stated above, the isobutane is a valuable constituent for the feed stock to the alkylation plant, while the normal butane is formed in a much lower proportion than in conventional pyrolytic processes.

While the presence of any amount of C₂ and C₃ hydrocarbons will suppress reactions (1) and (2) above to some extent, the effect increases with the amount of C₂ and C₃ hydrocarbons present. In order to obtain a substantial predominance of reaction (3) the C₂ and C₃ hydrocarbons should be present at least in equimolar proportion to the normal pentane, although a greater amount is to be preferred and a ratio of C₂ and C₃ hydrocarbons to normal pentane of 3:1 or greater is desired. Excellent results have been obtained using a molal ratio of about 7:1. In the C₂ and C₃ hydrocarbons charged as above, a ratio of 20% C₂ and 80% C₃ hydrocarbons has been found to give good results.

In carrying out the process of the invention it may be convenient to use a conventional thermal polymerization plant. The accompanying drawing shows diagrammatically a typical thermal polymerization plant with modifications for carrying out the invention. In accordance with the invention normal pentane in line 1 and C₂ and C₃ hydrocarbons in line 2 are charged to pyrolytic zone 6 through line 5; the proportion of each being controlled by valves 3 and 4. In pyrolytic zone 6 the mixture is heated to the reaction temperature in coils 7 and 8 and the resulting products leave through line 9. Suitable pressure is maintained upon the mixture in the pyrolytic zone by means of valve 10. From line 9 the products enter fractionating zone 11 (which may advantageously comprise several fractionating columns arranged in accordance with well known principles of fractional distillation) wherein they are fractionally distilled to recover desired fractions, shown diagrammatically as leaving through lines 12, 13, 14, 15, and 16 in the respective order of their boiling ranges. Through line 12 is withdrawn methane, and any hydrogen, formed during the reaction and sufficient ethane and ethylene to maintain the concentration of C₂ fractions withdrawn through line 13 within the desired range. This fraction may be used as fuel. The remaining C₂ hydrocarbons together with the C₃ hydrocarbons are withdrawn through line 13 and recycled to the process through lines 17 and 18, being mixed with incoming fresh charge of C₂ and C₃ hydrocarbons in line 2 or 5. Through line 14 is withdrawn the desired C₄ cut which under the operating conditions of the invention will contain from 60% to 80% of olefins. As previously stated, this C₄ cut may advantageously be used as olefinic feed for an alkylation process. Through line 15 is withdrawn a debutanized polymer gasoline while polymer tars leave the fractionating zone through line 16. If desired, normal pentane may be fractionated from the polymer gasoline in a second fractionating zone (not shown) and recycled to the process (through lines not shown) to be mixed with the fresh normal pentane in line 1 or 5.

Normal pentane for conducting the process of the invention is readily available in most refineries manufacturing aviation gasoline, being obtained as a by-product of relatively low value in the fractionation of straight run gasoline stocks, and other stocks, for the production of isopentane used as an ingredient in aviation gasoline. As is

well known, the normal pentane thus obtained is generally not of 100% purity. Modern fractionating equipment, carefully operated, is capable of producing normal pentane of 95% or higher purity. With less efficient equipment, or with overloaded efficient equipment, the purity of the normal pentane by-product may be reduced to as low as 75%, the chief impurity being isopentane.

While, for overall refinery efficiency, it is desirable to separate normal pentane of as high purity as possible, the process of the invention is adapted to operate satisfactorily on normal pentane stocks within the above range of purity. In the appended claims this range of purity is intended to come within the scope of the term "consisting essentially of normal pentane."

Following is an example of the process of the invention conducted in a conventional thermal polymerization plant. A fresh charge consisting of 612 barrels per day of propylene, 237 barrels per day of propane, and 1046 barrels per day of normal pentane stock, together with 3800 barrels per day of recycled C₃ hydrocarbons and 1162 barrels per day of recycled C₂ hydrocarbons, was charged to the heating coil of the polymerizing plant wherein the temperature was raised to 1125° F. The products from the heating coil were passed to the reaction section wherein the temperature was reduced to 1050° F. over a period of about 12 minutes. The products were then fractionally distilled into a gas fraction, a recycle fraction consisting of all the C₃ hydrocarbons together with a portion of the C₂ hydrocarbons formed, a C₄ cut containing all the C₄ hydrocarbons formed, a debutanized polymer gasoline fraction, and a residual tar fraction. It was found that the C₄ fraction contained 70% of olefins. The following table shows results obtained compared to conventional operations where C₃ hydrocarbons are polymerized under similar operating conditions:

	Process according to invention	Conventional thermal polymerization
45		
50	Fresh charge (bbl./day): Propylene.....	612
	Propane.....	237
	N-pentane stock.....	1,046
	Total.....	1,895
	Recycle stock (bbl./day): C ₃ hydrocarbons.....	1,162
	C ₂ hydrocarbons.....	3,800
55		4,962
	Analysis of N pentane stock, percent: Iso-pentane.....	17
	N-pentane.....	73
	Isobutane plus.....	6
60		4,962
	Yields (bbl. day): Isobutane.....	33
	Butylenes.....	202
	N-butane.....	54
	Total C ₄ fraction.....	289
	Other products.....	1,606
65		849
	Total.....	1,895
	Analysis of C ₄ fraction, (percent): Isobutane.....	11.4
	Butylenes.....	70.0
	N-butane.....	18.6
70		100.0
	Total.....	100.0

From the above table it is seen that, by introducing normal pentane into the charging stock of the polymerization plant in accordance with the invention, the yield of C₄ hydrocarbons is greatly increased together with a substantial over-

all lowering of the percentage of normal butane therein.

Although a conventional thermal polymerization plant using normal operating conditions of time, temperature, and pressure is well adapted to the carrying out of the invention and although such operation is a preferred form of the invention, the invention in a broader sense is not limited to such operation. Any equipment may be used which is capable of maintaining the mixture of normal pentane and C₂ and C₃ hydrocarbons at a cracking temperature for sufficient time that the desired amount of butylenes is formed and various apparatus may suggest themselves to a skilled engineer.

Conventional polymerization furnaces are generally divided into two sections; the tubes or coils of the first section being subjected to a higher degree of heat than those of the second section. The process of the invention may be carried out in a single coil subjected to the necessary temperature, or a combination of heating coil and reaction chamber may be used if so desired.

Pressures employed in conventional polymerization plants are usually in the order of 300 to 500 lbs. per sq. inch at the outlet transfer line. While this pressure is preferable, for operating reasons, in the practice of the invention, other pressures may be used from atmospheric, or below, to one hundred or more atmospheres.

Fractionation is, in practically all cases, carried out in a series of fractionating columns under pressures sufficient to properly condense the necessary products and refluxes at the temperatures employed. The conditions of operation and design of such fractionating towers is well known to distillation engineers.

Likewise, the charge to the conventional polymerization plant (including both the feed and recycle stocks) is generally in the liquid phase. This is, however, merely an expedient and the charge of normal pentane and C₂ and C₃ hydrocarbons according to the invention may be either in the liquid or vapor phase as desired. Obviously, at the cracking temperatures involved, the materials undergoing the reactions will be above the critical temperature, and, consequently, in the vapor phase.

We claim:

1. The process of producing a mixture of C₄ hydrocarbons containing a high proportion of butylenes, which comprises: subjecting a hydrocarbon fraction consisting essentially of normal pentane to a temperature in the range of 1000° F. to 1300° F. while in the presence of added amounts of hydrocarbons from the group consisting of ethane, ethylene, propane, and propylene and in the substantial absence of other added hydrocarbons; fractionally distilling the resulting products; and separating therefrom a mixture of C₄ hydrocarbons; the molal ratio of normal pentane to C₂ and C₃ hydrocarbons subjected to the reaction being between about 1:1 and about 1:7.

2. The process according to claim 1 wherein the molal ratio of normal pentane to C₂ and C₃ hydrocarbons subjected to the reaction is not greater than 1:3.

3. The process according to claim 1 wherein the molal ratio of normal pentane to C₂ and C₃ hydrocarbons subjected to the reaction is about 1:7.

4. The process of producing a mixture of C₄ hydrocarbons containing a high proportion of butylenes, which comprises: subjecting a hydrocarbon fraction consisting essentially of normal pentane to a temperature in the range of about 1050° F.

to about 1150° F. while in the presence of added amounts of hydrocarbons from the group consisting of ethane, ethylene, propane, and propylene and in the substantial absence of other added hydrocarbons; fractionally distilling the resulting products; and separating therefrom a mixture of C₄ hydrocarbons; the molal ratio of normal pentane to C₂ and C₃ hydrocarbons subjected to the reaction being between about 1:1 and about 1:7.

5. The process of producing a mixture of C₄ hydrocarbons containing a high proportion of butylenes, which comprises: flowing a stream of hydrocarbons consisting essentially of normal pentane through a conduit, simultaneously flowing a stream of hydrocarbons from the group consisting of ethane, ethylene, propane, and propylene through said conduit in admixture with said normal pentane while in the substantial absence of other added hydrocarbons, heating the mixture in said conduit to a temperature between 1000° F. and 1300° F., maintaining the mixture at said temperature for sufficient time that a portion of the normal pentane is cracked forming butylenes, reducing the temperature of the resulting products, fractionally distilling the resulting products and separating therefrom a fraction composed mainly of the C₄ hydrocarbons present in said products; the molal ratio of normal pentane to C₂ and C₃ hydrocarbons subjected to the reaction being between about 1:1 and about 1:7.

6. The process of producing a mixture of C₄ hydrocarbons containing a high proportion of butylenes, which comprises: flowing a stream of hydrocarbons consisting essentially of normal pentane through a conduit, simultaneously flowing a stream of hydrocarbons from the group consisting of ethane, ethylene, propane, and propylene through said conduit in admixture with said normal pentane while in the substantial absence of other added hydrocarbons, heating the mixture in said conduit to a temperature between 1000° F. and 1300° F., maintaining the mixture at said temperature for sufficient time that a portion of the normal pentane is cracked forming butylenes, reducing the temperature of the resulting products, fractionally distilling the resulting products to separate therefrom a fraction composed mainly of the C₄ hydrocarbons present in said products and a recycle fraction composed mainly of C₂ and C₃ hydrocarbons, and returning at least a portion of said recycle fraction to the process to join said stream of C₂ and C₃ hydrocarbons; the molal ratio of normal pentane to C₂ and C₃ hydrocarbons subjected to the reaction being between about 1:1 and about 1:7.

7. The process of producing a mixture of C₄ hydrocarbons containing a high proportion of butylenes, which comprises: flowing a stream of hydrocarbons consisting essentially of normal pentane through a conduit, simultaneously flowing a stream of hydrocarbons from the group consisting of ethane, ethylene, propane, and propylene through said conduit in admixture with said normal pentane while in the substantial absence of other added hydrocarbons, heating the mixture in said conduit to a temperature between 1000° F. and 1300° F., maintaining the mixture at said temperature for sufficient time that a portion of the normal pentane is cracked forming butylenes, reducing the temperature of the resulting products, fractionally distilling the resulting products to separate therefrom a fraction composed mainly of the C₄ hydrocarbons present in said products and a recycle fraction composed mainly of unrefined

acted normal pentane, and returning at least a portion of said recycle fraction to the process to join said first mentioned stream; the molal ratio of normal pentane to C₂ and C₃ hydrocarbons subjected to the reaction being between about 1:1 and about 1:7.

8. A method comprising thermally cracking at a temperature in the order of 1000° F. to 1300° F. a mixture of normal pentane, C₂ hydrocarbons and C₃ hydrocarbons while in the substantial absence of other added hydrocarbons and fractionally distilling a C₄ fraction from the resulting products; the molal ratio of normal pentane to C₂ and C₃ hydrocarbons subjected to the reaction being between about 1:1 and about 1:7, and said C₂ and C₃ hydrocarbons being taken from the group consisting of ethane, ethylene, propane, and propylene.

9. A process of producing C₄ hydrocarbons which comprises: heating normal pentane to a cracking temperature in the order of 1000° F. to 1300° F. while in the presence of an added quantity of C₂ and C₃ hydrocarbons and in the substantial absence of other added hydrocarbons, and maintaining such temperature for a period of time sufficient to form a C₄ fraction containing in the order of from 60% to 80% of olefins; the molal ratio of normal pentane to C₂ and C₃ hydrocarbons subjected to the reaction being between about 1:1 and about 1:7, and said C₂ and C₃ hydrocarbons being taken from the group consisting of ethane, ethylene, propane, and propylene.
